UNITED STATES PATENT OFFICE.

HORATIO SMITH, OF KIDDERMINSTER, ENGLAND, ASSIGNOR TO JAMES HUMPHRIES & SONS, OF SAME PLACE.

DESIGN FOR CARPET.

Specification forming part of Design No. 6,888, dated September 16, 1873; application filed August 30, 1873.
[Term of Patent 3½ years.]

To all whom it may concern:

Be it known that I, HORATIO SMITH, designer, of Kidderminster, county of Worcester, England, have invented a new and original Design for Carpets; and I do hereby declare that the following is a full, clear, and exact description thereof, which will enable others skilled in the art to make and use the same, reference being had to the accompanying photographic illustration, forming part of the specification, viz: Design in Louis-quatorze style, ornament forming panels containing groups of flowers.

The nature of my design is fully represented in the accompanying photographic illustration, to which reference is made.

a represent alternate panels; *b* the central group of flowers. One of these panels is formed by a succession of arcs of circles, *d*,

in one case forming a border broken at four points by a projecting shield, *e*, with wreaths of flowers *f* inside the border. The other panel approaches a square with the central group of flowers *b*, and with four small clusters of flowers; *g*, outside the border on dark grounds *h*. The central clusters *b* in both panels rest on a dark ground, *i*. The design outside the panels consists of a ground varying in shade from light to dark, interspersed with shrubbery, flowers, and dark figures *k*, with inclosed tracery *l*.

I claim as my invention—

The design for carpets, as shown.

HORATIO SMITH.
